(57) **CLAIM**

The ornamental design for a tactical carbon guard for a firearm mounted flashlight, as shown and described.

DESCRIPTION

FIG. 1 is an isometric view showing my new design for a tactical carbon guard for a firearm mounted flashlight, FIG. 2 is a front view thereof, FIG. 3 is a rear view thereof, FIG. 4 is a side view thereof, FIG. 5 is a top view thereof, FIG. 6 is a bottom view thereof; and, FIG. 7 is an isometric view of a preferred embodiment showing the tactical carbon guard for a firearm mounted flashlight in use. The broken lines as shown in FIG. 7 form no part of the claimed design.
